UNITED STATES PATENT OFFICE.

EDWARD ABORN, OF EAST ORANGE, NEW JERSEY.

DESIGN FOR A FILTER COFFEE-POT.

54,810.

Specification for Design.

Patented Mar. 30, 1920.

Application filed June 16, 1919. Serial No. 304,700. Term of patent 14 years.

To all whom it may concern:

Be it known that I, EDWARD ABORN, a citizen of the United States, residing at East Orange, in the county of Essex and State of New Jersey, have invented a certain new and original ornamental Design for a Filter Coffee-Pot, of which the following is a specification, reference being had to the accompanying drawing, forming part thereof.

The figure is a side elevation of a filter coffee pot showing my new design.

I claim:

The ornamental design for a filter coffee pot as shown.

In testimony that I claim the foregoing, I have hereunto set my hand this 10th day of June, 1919.

EDWARD ABORN.
